PHILIP TORCHIO AND HARRY R. WOODROW, OF NEW YORK, N. Y., ASSIGNORS TO
THOMAS E. MURRAY, OF NEW YORK, N. Y.

REACTANCE-COIL.

1,235,081.

Specification of Letters Patent. Patented July 31, 1917.

Application filed March 15, 1917. Serial No. 155,064.

To all whom it may concern:

Be it known that we, PHILIP TORCHIO and HARRY R. WOODROW, citizens of the United States, residing at New York, in the county of New York and State of New York, have invented a certain new and useful Improvement in Reactance-Coils, of which the following is a specification.

The invention relates to reactance coils for high tension voltage. Such coils are commonly used in series with high speed alternating current generators to limit the instantaneous inrush of current under short circuit conditions, thus relieving the generator winding from abnormal stresses, and facilitating the parallel operation of other generators and synchronous apparatus in the system.

The invention consists, first, in the construction of the individual coils and the transposition of the conductors in the windings thereof, and, second, in the construction of the casing wherein said coils are supported and inclosed—all as more particularly hereinafter set forth.

In the accompanying drawings—

Figure 1 is a perspective view of our reactance coils, with portions broken away to show the internal construction. Fig. 2 is a face view of one of the coils, showing also the vertical spacing bars in dotted lines. Fig. 3 is a top view of the coils, showing the spacing bars in place. Fig. 4 is a vertical section on the line x, x of Fig. 1. Fig. 5 is a diagonal section on the line y, y of Fig. 1. Fig. 6 shows the coils in vertical section, with the windings somewhat separated to exhibit the winding connections. Fig. 7 is an enlarged vertical section of the top portion of the coils and spacing bars on the line z, z of Fig. 3.

Similar numbers and letters of reference indicate like parts.

Referring first to Fig. 6: A, B, C, D, E represent five coils of the so-called "pancake" type, formed of flat strips of conducting material covered with insulation. Each coil has five windings, 1, 2, 3, 4, 5. The innermost winding 1, which is nearest the center of the coil, is here shown with seven turns; the winding 2 with six turns; the winding 3 with five turns; the winding 4 with four turns, and the outermost winding 5 with three turns. These particular numbers of turns in the several windings

are not essential to our invention, since they may be varied, as will be explained further on.

The connections between the windings are such that the windings 1, 2, 3, 4 of coils B, C, D, E are each connected to the winding next outside and to the left. Thus, winding 1 of coil E is connected to winding 2 of coil D; winding 2 of coil D to winding 3 of coil C; winding 3 of coil C to winding 4 of coil B, and winding 4 of coil B to winding 5 of coil A. The windings 1, 2, 3, 4 of coil A are connected respectively to windings 2, 3, 4, 5 of coil E. The unconnected terminals of windings 1 of coils A, B, C, D, E are all connected to the bent over end portion F of a metal lead G, and the unconnected terminals of windings 5 of said coils are all connected to the bent over end portion H of a metal lead I. The several coils A, B, C, D, E are thus connected in multiple with the leads G, I. There are as many "pancake" coils A, B, C, D, E as there are conductors, and every conductor is wound in every coil.

The number of turns of the several windings decrease from the center to the circumference of the coils, and, generally, this number is to be so determined as that the drop of potential in each winding shall be the same. This is illustrated by making, as already explained, the inner windings 1 of seven turns, with the turns of the other windings successively decreasing finally to three turns in the circumferential windings 5. By reason of this construction and because of the parallelism of the coils, there is no accumulation of potential between said coils. This permits of a much shorter device as a whole in order to withstand the applied potentials, obviates the use of insulating partitions between the coils, requires less copper, and involves less losses in attaining the same reactance value.

The coils A, B, C, D, E are separated by parallel wooden bars 6, 7, 8, 9, disposed in the intervening spaces, said bars projecting at each end beyond the circumferences of the coils. Between the protruding ends of said bars are spacing blocks 10 which are curved to fit upon the coil peripheries. Rods 11—preferably covered with shellac—are received in registering openings in said bars and spacing blocks, as shown in Fig. 7.

The casing has two rectangular and paral-

lel walls 12, 13 of porcelain. Between said walls and at the upper corners of the same are interposed two series of porcelain blocks—one of said series being numbered 14, 15, 16, 17, 18, 19. The outer edges of said blocks register with the corresponding edges of the walls 12, 13. The inner corners of blocks 15, 16, 17, 18 are suitably formed to fit against the circumferential periphery of the coils. The blocks 14, 19 at the ends of the series at their inner corners have integral arms 20, 21, Fig. 5, which extend over the outer faces of coils A and E.

Between said walls 12, 13 and at the lower corners of the same are interposed two series of porcelain blocks—one of said series being numbered 22, 23, 24, 25, 26, 27. The outer edges of said blocks register with corresponding edges of the walls 12, 13, and the inner corners of blocks 23, 24, 25, 26 are suitably formed to fit against the circumferential periphery of the coils. The blocks 22, 27 of both series at their corners have integral arms 29, 30, similar to arms 20, 21, which also extend over the outer faces of coils A and E, and between said faces and the walls 12 and 13. Headed bolts 31, preferably inclosed in insulating tubes, extend through said walls and blocks, and clamp all parts together. The blocks may also be cemented together.

In the lower faces of the upper series of interposed blocks and in the upper faces of the lower series of interposed blocks on each side of the casing are grooves 32, into which may be slid panels 33, Fig. 1, for closing the rectangular space between said upper and lower blocks and said walls 12, 13. In the opposite faces of the two series of interposed blocks above the coils are grooves which receive wooden bars 34, and in the opposite faces of the two series of interposed blocks below the coils are grooves which receive wooden bars 35. There are intervals between said bars to provide for the ventilation of the inclosed coils, due to the natural draft induced by the radiated heat from the windings.

The leads G, I are inclosed in quadrangular bushes 36, 37, of insulating material. The inner wall of each bush is cut away to form a shoulder, which shoulders rest upon two of the bars 34. The lead G extends through the channel between the three remaining bush walls; the lead I does not, because the horizontal bent portion H of lead I connects, as already explained, with windings 5, while the horizontal bent portion F of lead G connects with windings 1 of coils A, B, C, D, E.

We claim:

1. A reactance apparatus, comprising a plurality of parallel coils in "pancake" form connected in multiple, each coil comprising a

plurality of concentric windings, there being as many of said "pancake" coils as there are conductors in said windings, and each conductor being wound in every "pancake" coil.

2. A reactance apparatus, comprising a plurality of parallel coils in "pancake" form connected in multiple, each coil comprising a plurality of concentric windings; the said windings being interconnected so that the potential between the terminals of each coil shall be equally distributed among the terminals of the several windings composing said coil.

3. A reactance apparatus, comprising a plurality of parallel coils in "pancake" form connected in multiple, each coil comprising a plurality of concentric windings; the turns of said windings decreasing in number from the inner to the outer winding, whereby the potential between the terminals of each coil shall be equally distributed among the terminals of the several windings composing said coil.

4. A reactance apparatus, comprising a casing, comprising two rectangular walls of insulating material, and between said walls a plurality of parallel coils in "pancake" form and four series of parallel spacing blocks, the said blocks being symmetrically disposed around said coils and having their exposed faces registering with the edges of said walls adjacent to the angles thereof, and means for clamping together said blocks and said walls.

5. A reactance apparatus, comprising a casing, comprising two rectangular walls of insulating material, and between said walls a plurality of parallel coils in "pancake" form and four series of parallel spacing blocks, the said blocks being symmetrically disposed around said coils and having their exposed faces registering with the edges of said walls adjacent to the angles thereof, two outer blocks of each series having inwardly projecting arms extending over the outer faces of the outer coils, and means for clamping together said blocks and said walls.

6. A reactance apparatus, comprising a casing, comprising two rectangular walls of insulating material, and between said walls a plurality of parallel coils in "pancake" form and four series of parallel spacing blocks, the said blocks being symmetrically disposed around said coils and having their exposed faces registering with the edges of said walls adjacent to the angles thereof, means for clamping together said blocks and said walls, and removable means for closing the openings between the members of two pairs of said four series of spacing blocks.

7. A reactance apparatus, comprising a casing, comprising two rectangular walls of insulating material, and between said walls

a plurality of parallel coils in "pancake" form and four series of parallel spacing blocks, the said blocks being symmetrically disposed around said coils and having their exposed faces registering with the edges of said walls adjacent to the angles thereof, means for clamping together said blocks and said walls, and a sliding panel received in grooves formed in the members of two pairs of said four series of spacing blocks for closing the opening between said members.

8. A reactance apparatus, comprising a plurality of parallel coils in "pancake" form, parallel spacing bars of insulating material between said coils, and a casing for said coils having openings communicating with the spaces between said bars, whereby a ventilating air current due to the heat radiated from

said coils is caused through said openings and said air spaces. 20

9. A reactance apparatus, comprising a plurality of parallel coils in "pancake" form, parallel spacing bars of insulating material between said coils and protruding beyond the circumferential peripheries of said coils, 25 spacing blocks of insulating material interposed between the protruding ends of said bars, and pins extending through said spacing blocks and said bars.

In testimony whereof we have affixed our 30 signatures in presence of two witnesses.
